UNITED STATES PATENT OFFICE.

MILTON MAYER, OF BURLINGTON, IOWA.

PUMP OIL CAN.

1,426,586.

Specification of Letters Patent. Patented Aug. 22, 1922.

Application filed May 28, 1920. Serial No. 384,826.

To all whom it may concern:

Be it known that I, MILTON MAYER, a citizen of the United States, residing at Burlington, in the county of Des Moines and 5 State of Iowa, have invented certain new and useful Improvements in Pump Oil Cans, of which the following is a specification.

This invention relates to oil cans and its 10 object is to provide an improved pump oiler for use by machinists and engineers in connection with automobiles, machines and engines.

The primary object of the invention is to 15 provide an oil can in which the pump has direct communication with the reservoir so that the oil may be lifted into the pump cylinder on one stroke of the piston by direct pump action and then forced on the return stroke of the piston through the discharge 20 pipe.

Another object of the invention is to provide 25 an oil can in which the delivery of oil is under positive manual control so that any desired quantity of oil may be discharged from the can without liability of waste.

Other objects of the invention are to arrange 30 the valves in a horizontal position so that they will seat properly and locate them adjacent the bottom of the oil reservoir so that they will always be primed by submersion in the oil; and also to provide an oiler of simple but strong and durable construction, efficient in operation, positive in action and inexpensive to manufacture.

With these and other ends in view which 35 will more fully appear in the detail description hereafter I have illustrated the invention in a selected embodiment in the accompanying drawings, in which—

Fig. 1 is a sectional view of an oil can 40 embodying my invention;

Fig. 2 is a perspective view of one of the valves; and

Fig. 3 is a detail sectional view showing a 45 slight modification in the construction.

Referring to the drawings, 4 is the body of the oiler which may be punched out at 5 to form a filling opening and its wall threaded to receive cap 6. The body may also be 50 punched out at 7 and threaded to receive the cap 8 which secures the spout 9 in place on the body. A pump cylinder 10 and a discharge cylinder 11 are engaged one with the other adjacent their inner ends and are 55 disposed angularly within the body. The pump cylinder 10 projects through an open-

ing in the body adjacent the filling opening 5 and is closed by a screw cap 12. This cylinder extends down close to the bottom of the body and a machined valve seat 13 having an opening 14 therein is soldered or otherwise suitably secured in the lower end of the cylinder. A valve 15 ground to snugly fit the seat 13 is normally held seated by a spring 16 embracing the valve and fastened to the seat. A piston comprising cups 17, 17' secured by washers 18, 18' on the piston 19 is arranged to operate in the pump cylinder and a spring 20 is arranged between the piston and the lower end of the discharge cylinder 11 which projects into the pump cylinder above the valve 15. A seat 21 similar to the seat 13 is secured in the lower end of the discharge cylinder 11 and is provided with an opening 22. A ground valve 23 is held against the seat 21 by a spring 24, the construction of the two valves being preferably the same. The springs 16 and 24 may be secured to their respective seats by solder, by welding or by any other suitable means. A hollow core 25 is arranged in the discharge cylinder 11. A suitable handle 26 is secured to the body.

In the construction of Fig. 3 that part 27 of the discharge cylinder 11' which enters 85 the pump cylinder 10' is bent downwardly and the valve seat 21' is secured to this down-turned part and to the pump cylinder.

In operation the pump cylinder is filled on the suction stroke of the piston induced 90 by the spring 20 during which the valve 23 is closed and valve 15 is opened. To screen the oil in filling the oiler I provide a perforated disk or screen 28 of foraminous metal which is secured in place at the bottom of the filling opening 5 in a peripheral notch or bead 29 formed in the wall of said opening. When the piston is depressed by pressure applied to the piston rod valve 15 remains closed and valve 23 100 is opened to permit discharge through the pump cylinder and the spout of the oil which has been drawn up into the pump cylinder. The quantity of oil discharged can be easily controlled by the operation of 105 the piston and in this way waste of oil is avoided.

I prefer to make each of the valves 15 and 23 in the form of a hollow cone with peripheral flanges 15' and 23' thereon 110 ground to fit the machined seats but the construction of these valves may be

changed, if desired, and the seats 13 and 21 may be provided and secured in the cylinders in other ways within the scope of my invention. The valves fit the seat 5 snugly and both are substantially parallel with the base of the oiler so that in the normal travel of the automobile or truck in which the oiler is stored flatly on its base, and the vibration incident to such travel, 10 the valves will not slide on their seats or become dislocated therefrom and therefore undue wear and leakage are avoided. Each valve makes a surface contact with its seat, and not a line contact, and thereby provides 15 an effectual seal which is especially desirable in an automobile oiler which is constantly subjected to vibration during the travel of the automobile. Both of the valves are located closely adjacent to the bottom 20 of the oiler so that they will be submerged in the oil and primed for a greater length of time than is usual in pump oilers. The two valves are located in such close relationship that a valve chamber is almost completely eliminated whereby a high degree 25 of efficiency is obtained since very little if any effort is wasted in exhausting the oil content of a large valve chamber which might be located between the intake valve 30 and the discharge valve. The hollow core or plug 25 in the discharge cylinder reinforces and strengthens the cylinder and the portion of the body in which the cylinder 35 is supported and the connection with the spout; and it also to a material extent prevents access through the cylinder to the valves and in this way serves as a protection against tampering and injuring the valves. My improved oiler is substantial 40 in construction, efficient in operation, and it can be manufactured at comparatively low cost. The horizontal arrangement of the valves and their location closely adjacent to the bottom of the oiler is especially 45 important because not only are the valves kept submerged and primed until the greater portion of the oil has been discharged but the location of the intake valve 50 is so close to the bottom of the body that practically every bit of oil in the oiler 55 may be discharged. The particular arrangement of the pump and cylinder and the discharge cylinder with their lower ends interengaged and with their upper ends engaged with and seated in the body makes a particularly strong and substantial structure and one which is highly efficient in operation.

I reserve the right to make all such changes in the form, construction and arrangement of parts of my invention as fairly fall within the scope of the following claims.

I claim:

65 1. An oil can comprising a body, a pump

cylinder supported in an angular position in the body and having at its lower end a flat valve seat parallel with the bottom of the body and located adjacent thereto, an intake valve on said seat, a spring pressed piston 70 operating in said pump cylinder, a discharge cylinder supported in the body at substantially a right angle to the pump cylinder and having its lower end projected into the pump cylinder and provided with a flat 75 valve seat adjacent to the intake valve and parallel with the bottom of the body, a discharge valve on said latter seat, and a spout communicating with said discharge cylinder. 80

2. An oil can comprising a body, a pump cylinder supported in an angular position in the body and having at its lower end a valve seat parallel with the bottom of the body and located adjacent thereto, an intake valve 85 on said seat, a discharge cylinder supported in an angular position in the body and having its lower end projected into the pump cylinder and provided with a valve seat adjacent to the intake valve and parallel with the bottom of the body, a discharge valve on 90 said latter seat, a spout communicating with said discharge cylinder, a piston operating in said pump cylinder, and a spring for said piston and supported in said pump cylinder 95 on the projecting end of the discharge cylinder.

3. An oil can comprising a body having a filling opening, a pump cylinder and a discharge cylinder disposed at substantially a 100 right angle to each other and having their upper ends supported in the wall of the body on opposite sides of said filling opening and the lower end of the discharge cylinder projected into the pump cylinder adjacent the 105 lower end of the latter, the pump cylinder having an opening in its lower end and a valve seat therefor and the discharge cylinder having an opening in that part of its end which projects into the pump cylinder and a valve seat therefor, valves for said seats, a spout communicating with said discharge cylinder, and a spring pressed piston operating in said pump cylinder. 110

4. An oil can comprising a body, a pump cylinder and a discharge cylinder supported in the wall of the body at substantially a right angle to each other with the lower end of the discharge cylinder projected into the pump cylinder adjacent its lower end, the pump cylinder having an opening in its lower end and a valve seat therefor located adjacent to and parallel with the bottom of the body, an intake valve for 115 said valve seat, the discharge cylinder having an opening in its lower end and a valve seat therefor located adjacent to the intake valve and parallel with the bottom of the body, a valve for said latter seat, the communicating ends of said cylinders with 120 125 130

the valve seats and valves being free from contact with the body end positioned substantially central of the bottom of the body, a spout communicating with the discharge cylinder, and a spring pressed piston operating in the pump cylinder.

5. An oil can comprising a body, having a filling opening, a pump cylinder and a discharge cylinder having their upper ends supported in a wall of the body on opposite sides of said filling opening, the lower end of the pump cylinder being located adjacent to the bottom of the body and having an opening and a valve seat therefor, the lower 10 end of the discharge cylinder being projected into the pump cylinder and having an opening and a valve seat therefor, said valve seats being parallel with the bottom 15 of the body and located in adjacent relation

close to said bottom, spring pressed valves 20 on said valve seats, a spout connected to said discharge cylinder, a piston operating in said pump cylinder, and a spring for said piston supported in the pump cylinder upon the end of the discharge cylinder projecting 25 thereinto.

6. An oil can comprising a body having a bottom, a cylinder supported in the body and having an opening in its lower end and a flat valve seat for said opening located adjacent to and substantially parallel with said bottom, a valve comprising a cone shaped central portion with a peripheral flange thereon to make flat surface contact with said seat, and a spring fastened to said cylinder and engaging said valve to hold it 30 yieldingly in place on said seat.

MILTON MAYER.
